CLAIM

The ornamental design for star jewelry ornament or the like, as shown and described.

DESCRIPTION

FIG. 1 is a front elevational view of a star jewelry ornament or the like showing my new design, the rear elevational view thereof being identical;

FIG. 2 is a front end view thereof, the left side, right side and rear end views thereof being identical;

FIG. 3 is a front elevational view of a star jewelry ornament or the like showing a modified form of my new design, the rear elevational view being identical; and

FIG. 4 is a front end view of the FIG. 3 embodiment, the left side, right side and rear end views thereof being identical.

FIG.1

FIG.2

FIG.3

FIG.4
